UNITED STATES PATENT OFFICE

JOHN HULL WHITCOMB, OF LAKWOOD, OHIO, ASSIGNOR TO THE B. F. GOODRICH COMPANY, OF NEW YORK, N. Y., A CORPORATION OF NEW YORK

DESIGN FOR A BATHING CAP

Application filed March 18, 1932. Serial No. 43,231. Term of patent 14 years.

To all whom it may concern:

Be it known that I, JOHN HULL WHITCOMB, a citizen of the United States, residing at Lakewood, in the county of Cuyahoga and State of Ohio, have invented a new, original, and ornamental Design for a Bathing Cap, of which the following is a specification, reference being had to the accompanying drawing, forming a part thereof.

Fig. 1 is a top view of a bathing cap showing my design.

Fig. 2 is a side elevation of the same cap as viewed from the right.

Fig. 3 is a side elevation of the same cap as viewed from the left.

I claim:

The ornamental design for a bathing cap as shown.

JOHN HULL WHITCOMB.
